UNITED STATES PATENT OFFICE.

HENRY B. NEWHALL, JR., OF PLAINFIELD, NEW JERSEY.

TOOL-HOLDING FLOOR-STAND.

1,167,921.

Specification of Letters Patent. Patented Jan. 11, 1916.

Application filed February 10, 1915. Serial No. 7,259.

To all whom it may concern:

Be it known that I, HENRY B. NEWHALL, Jr., a citizen of the United States, residing in Plainfield, in the county of Union and 5 State of New Jersey, have invented certain new and useful Improvements in Tool-Holding Floor-Stands, of which the following is a specification.

This invention relates to, and has for a 10 main object, to provide a movable floor stand for tools such as hammer drills or the like.

Other objects of the invention are to equip 15 such a floor stand with a platform on which the operator may sit when operating the tools supported by the floor stand; to provide such a floor stand whereby the attack of the tool onto the work or removal of the tool from such work may be accomplished 20 with great facility; to provide such a floor stand in which the supporting frame of the tool may be readily rotated in order to turn the tool in the hole for the purpose of clearance; and to provide a floor stand to which 25 a tool carrier can be attached ready for operation without reconstruction of such tool carrier. These and other features, capabilities and advantages of the invention will appear from the subjoined detailed description of one specific embodiment thereof illustrated in the accompanying drawings in which—

Figure 1 is a side elevation of the floor stand with a tool and tool carrier attached 35 thereto. Fig. 2 is a perspective of the same. Fig. 3 is a fragmentary perspective of a modification. Fig. 4 is a fragmentary perspective of the connection between the tool and the floor stand. Fig. 5 is a fragmentary 40 detail showing the pivotal connection between the upper end of the yoke and the tool carrier.

In the embodiment shown, there is provided a conveyance composed of a platform 45 substantially oblong in outline conformation, provided with three U-shaped brackets, one such bracket 11 disposed adjacent to and medially of the rear end of the platform 10 and the other two brackets 12, 12 disposed one at each side of and near the front end of the platform 10. Each of these brackets 11 and 12 is provided with a pivotally supported bearing 13 for a caster 14 by means of which the platform is movably 50 mounted. The rear bracket 11 is slightly shorter than the two front brackets 12 so

that the plane of the platform 10 when resting on all three casters 14 will be normally disposed at an inclined angle to the plane of the floor F (Fig. 1). The platform 10 has a forwardly extending tongue shaped member 15 to the lower side of which is secured an extension comprising a flat bar 16, in the present instance, such flat bar having a bend 17 just forwardly of the front end 60 of the tongue 15 so that the front portion 18 of the bar 16 is disposed in a lower plane than the rear portion 19 of such bar. Near the front end of the portion 18, there is provided an opening in which the cylindrical collar 20 is disposed having a lower outstanding annular portion 21 to rest adjacent the lower surface of the portion 18 and an upper outstanding annular portion 22 spaced apart from said portion 18 a predetermined 65 distance, said collar being mounted to swivel 70 in the opening formed in said portion 18.

In the construction illustrated in Figs. 1 and 2, a hammer drill and the yoke for supporting the same are mounted on the 80 portion 18 of the platform 10 and secured to one another so as to swing as a unit relative to said portion 18. The yoke of this construction is designated as 24 and has a lower end 23 (see Fig. 4) secured between 85 the portion 18 and the upper outstanding annular portion 22 of the collar 20, and an upper end 25. Between the upper end and the lower end of the yoke 24, there is secured the hammer drill 26 having a casing 27 provided with a belly portion 28 from one side of which extends a handle 29 for operating the hammer drill, and a guiding handle 30 at the upper end of said casing, and a bit 31 at the lower end thereof, which bit extends through the collar 20, being reciprocably mounted therein, the shoulder 32 at the lower end of the hammer drill resting on the upper edge of said collar 20. The upper end 25 of the yoke 24 is pivotally 90 connected to the upper end of the casing 27 inside of the handle 30 by means of a bolt 33. This bolt 33, as shown in Fig. 5, has a screw-threaded connection with the upper end 25 of the yoke 24, terminating at its 95 lower end in a pivotal pin 36 which is adapted to engage in an orifice 37 formed in the upper end of the casing 27 inside of the handle 30 as shown. By this arrangement, it is made possible to use any of the standard tool carriers of the character described, 100 and by merely forming the orifice 37, to 105 110

5 prepare the tool carrier ready for use with the present movable floor stand, since when it is desired to equip the floor stand with a tool carrier, it is only necessary to guide the lower end of the tool carrier so that its shoulder 32 will rest on the upper edge of the collar 20, then swing the casing 27 over so that its upper end is disposed under the upper end 25 of the yoke 24, the pin 36 located in the orifice 37 and the bolt 33 screwed down into a position where it is locked by the lock-nut 38 and where it will pivotally lock the tool carrier in place. And on the other hand, when it is desired to remove such tool carrier, it is only necessary to unscrew the bolt 33 to free the upper end of the tool carrier, swing it out of engagement with such yoke and withdraw the lower end from the collar 20. The yoke 24 10 which for convenience of description is termed the close yoke, has its main portion lying substantially close to the casing 27 and is provided with a handle 34 on the side of it removed from the casing 27, which handle 34 in the present instance is provided with a stud 40 (Fig. 2) extending through the yoke 24 and into that side of the belly portion 28 of the casing 27 which is opposite to the side on which the handle 29 is secured whereby the yoke 24 is fixed to 15 swivel with the casing 27.

In the construction shown in Fig. 3, instead of the close yoke 24, there is provided a bowed yoke 39 which bulges out beyond the fixed handle 35 secured to that side of the belly portion 28 which is opposite to the side thereof to which the operating handle 29 is secured. The bowed yoke 39 has its upper end 25 and its lower end 23 secured in place substantially in the same manner as is the case with the close yoke 24 except that this yoke 39 is not fastened to the belly portion 28 so that it will be compelled to rotate with such casing 27, but on the other hand, the connection of the pivotal pin 36 disposed in the orifice 37 at the upper end of the casing 27, and the connection of the lower end 23 of the yoke 39 with the collar 22 will be sufficiently free to permit the hammer drill 26 to freely swivel relative to said bowed yoke 39 and thereby permit proper turning of the drill to provide clearance of the bit in the hole.

In the operation of the device, the operator will sit on the platform 10 and move the platform around to the location of the work. When he is ready to commence the operation, he will shift forward a trifle so that the platform will tilt from the dotted line position to the full line position shown in Fig. 1, where the hammer drill will be in contact with the work to be operated upon and ready to be operated. When the operator wishes to withdraw the tool from the work, by shifting rearwardly of the platform, the

platform will tend to tilt back into the dotted line position and thus automatically withdraw the tool from the work.

The hammer drill 26 is secured to the portion 18 at an angle substantially at right angles to the plane of the platform 10, so that when the platform is tilted forwardly in which the plane of the platform will be disposed substantially parallel to the plane of the floor F, then the hammer drill will be disposed substantially at right angles to the plane of the floor F, and thus be enabled to attack the work in a practically vertical line.

It is obvious that various changes and modifications may be made in the details of construction without departing from the general spirit of the invention.

I claim:

1. In a device of the character described, the combination with a conveyance on which the operator may sit, comprising a platform supported on casters by means of which the platform may be shifted from place to place, of an extension at one end of said platform, a yoke secured to said extension, there being openings in the upper end of said yoke, in the lower end of said yoke, and through the extension adjacent to said yoke all in alignment with one another, a tool carrier swivelly supported in said openings, a tool carried by said tool carrier and extending through the lower end of said yoke and through said extension to be in position to be operated by the operator seated on the platform.

2. In a device of the character described, the combination with a conveyance on which the operator may sit, comprising a platform movably supported, of an extension at one end of said platform, a yoke secured to said extension, there being openings in the upper end of said yoke, in the lower end of said yoke, and through the extension adjacent to said yoke all in alignment with one another, a tool carrier swivelly supported in said openings, a tool carried by said tool carrier and extending through the lower end of said yoke and through said extension to be in position to be operated by the operator seated on the platform.

3. In a device of the character described, the combination with a conveyance on which the operator may sit, comprising a support movably mounted, of a yoke secured to said support, there being openings in the upper end of said yoke, in the lower end of said yoke, and through said support adjacent to said yoke all in alignment with one another, a tool carrier swivelly supported in said openings, and a tool carried by said tool carrier and extending through the lower end of said yoke and through said support to be in position to be operated by the operator seated on the support.

4. In a device of the character described, the combination with a conveyance on which the operator may sit comprising a platform, of casters on which said platform is movably mounted, a pair of said casters being disposed adjacent to the front end of said platform, an extension secured at such front end of said platform, a yoke secured to such extension, there being openings in the upper end of said yoke, in the lower end of said yoke, and through the extension adjacent to said yoke all in alinement with one another, a tool carrier swivelly supported in said openings, a tool carried by said tool carrier and extending through the lower end of said yoke and through said extension to be in position to be operated by the operator seated on said platform, the platform being tiltably mounted with said pair of casters as a fulcrum.

5. In a device of the character described, the combination with a conveyance on which the operator may sit comprising a platform, of casters on which said platform is movably mounted, a pair of said casters being disposed adjacent to the front end of said platform, an extension secured at such front end of said platform, a yoke secured to such extension, there being openings in the upper end of said yoke, in the lower end of said yoke, and through the extension adjacent to said yoke all in alinement with one another, a tool carrier swivelly supported in said openings, a tool carried by said tool carrier and extending through the lower end of said yoke and through said extension to be in position to be operated by the operator seated on said platform, the platform being tiltably mounted with said pair of casters as a fulcrum, said platform being disposed at an inclined angle to the floor on which it is supported when in raised position, said tool being disposed substantially at right angles to said platform.

6. In a device of the character described, the combination with a conveyance on which the operator may sit, comprising a platform supported on casters by means of which the platform may be shifted from place to place, of an extension at one end of said platform, a yoke secured to said extension, there being openings in the upper end of said yoke, in the lower end of said yoke, and through the extension adjacent to said yoke all in alinement with one another, a rotary drill casing swivelly supported in said openings, a tool carried by said casing and extending through the lower end of said yoke and through said extension to be in position to be operated by the operator seated on the platform, a handle for operating said tool and extending from the side of said casing, and a second handle on said yoke, said casing being fastened to said yoke so that said second handle may be used for steadyng or turning the casing.

7. In a device of the character described,

the combination with a conveyance on which the operator may sit, of a yoke at one end of the conveyance for supporting a tool carrier ready for operation, said yoke being adapted to receive and fasten a standard tool carrier of the class described without reconstruction and comprising a lower end piece having an opening in which the lower end of the tool carrier is disposed, and an upper end piece having a bolt, said bolt terminating in a pivotal pin in its lower end, and there being an orifice in the upper end of said tool carrier into which the pivotal pin of said bolt may engage to pivotally lock the tool carrier in place.

8. In a device of the character described, the combination with a conveyance on which the operator may sit, comprising a platform supported on casters by means of which the platform may be shifted from place to place, of an extension at one end of said platform, a yoke secured to said extension, there being openings in the upper end of said yoke, in the lower end of said yoke, and through the extension adjacent to said yoke all in alinement with one another, a rotary drill casing swivelly supported in said openings, a tool carried by said casing and extending through the lower end of said yoke and through said extension to be in position to be operated by the operator seated on the platform, a handle for operating said tool and extending from the side of said casing, and a second handle on said yoke, said casing being fastened to said yoke so that said second handle may be used for steadyng or turning the casing.

9. In a device of the character described, the combination with a conveyance on which the operator may sit, comprising a platform, of mounting means disposed adjacent to the front end of said platform for movably mounting said platform, an extension secured at such front end of said platform, a yoke secured to such extension, there being openings in the upper end of said yoke, in the lower end of said yoke, and through the extension adjacent to said yoke all in alinement with one another, a tool carrier swivelly supported in said openings, a tool carried by said tool carrier and extending through the lower end of said yoke and through said support to be in position to be operated by the operator seated on said platform, the platform being tiltably mounted about said mounting means.

10. In a device of the character described, the combination with a conveyance on which the operator may sit, comprising a platform, of mounting means disposed adjacent to the front end of said platform for movably mounting said platform, an extension secured at such front end of said platform, a yoke secured to such extension, there being openings in the upper end of said yoke, in the lower end of said yoke, and through the lower end of said yoke, and through the

extension adjacent to said yoke all in alignment with one another, a tool carrier swivelly supported in said openings, a tool carried by said tool carrier and extending through the lower end of said yoke and through said support to be in position to be operated by the operator seated on said platform, the platform being tiltably mounted about said mounting means, said platform being dis-

posed at an inclined angle to the floor on which it is supported when in raised position, and said tool being disposed substantially at right angles to said platform.
